(57) **CLAIM**

The ornamental design for an enclosure for camera-equipped smartphone, as shown and described.

DESCRIPTION

FIG. 1 is a side view showing my new design for an enclosure for camera-equipped smartphone;

FIG. 2 is a rear view of the enclosure for camera-equipped smartphone of FIG. 1;

FIG. 3 is a front view of the enclosure for camera-equipped smartphone of FIG. 1;

FIG. 4 is a top view of the enclosure for camera-equipped smartphone of FIG. 1;

FIG. 5 is a bottom view of the enclosure for camera-equipped smartphone of FIG. 1; and,

FIG. 6 is a perspective view of the enclosure for camera-equipped smartphone of FIG. 1.

The broken lines depict portions of the enclosure for camera-equipped smartphone that form no part of the claimed design. The portions between the break lines form no part of the claimed design.
